United States Patent Office.

JOHN LIMING, OF PHILADELPHIA, PENNSYLVANIA, ASSIGNOR TO HIMSELF AND CHARLES C. SAVERY, OF SAME PLACE.

Design No. 5,031, dated June 20, 1871.

DESIGN FOR A WATER-COOLER AND REFRIGERATOR.

The Schedule referred to in these Letters Patent and making part of the same.

To all whom it may concern:

Be it known that I, JOHN LIMING, of the city of Philadelphia, in the State of Pennsylvania, have invented and produced a new, useful, and original Design for a Combined Portable Water-Cooler and Refrigerative Vessel, of which the following is a specification.

The nature of my design consists in the arrangement of a water-cooler within a circular wooden vessel lined inside with sheet metal, and provided with a removable cover in such manner and form that, while the inclosed cooler will serve, in hot weather, as a reservoir for iced water which may be drawn therefrom, at pleasure, by a stop-cock projecting through the inclosing vessel, the latter will serve as a refrigerative-vessel for preserving butter, milk, and other articles of food, and the two parts together form a portable vessel which will occupy but a comparatively small space and can be readily moved or carried from place to place by one person, the object of my invention being to afford a cheap and reliable combined water-cooler and refrigerative-vessel for those whose dwellings and circumstances will not permit the use of the larger and more costly coolers and refrigerators in common use; and my said design is fully represented in and by the accompanying drawing, to which reference is made—

Figure 1 being a central vertical section on the dotted line *v w* of Fig. 2, and

Figure 2 a plan view of the vessel without the cover.

A B is a coopered wooden circular vessel, having

an inside lining, *a'*, of sheet metal, and a removable cover, *b'*.

C D is an ice and water-receiving vessel of sheet metal or porcelain-lined cast-iron, of a segmental form in its horizontal section, fitted and secured to a portion of the curved inner side of the lining of the vessel A B, and thus leaving the larger portion *b''* of the vessel A B for a provision-chamber, and to be kept cool or refrigerative by contact with the broad side of the water-cooler C D.

The top of the cooler C D is fitted with a cap, *c'*, which slips tightly over a flange around its mouth, and closely down upon a vulcanized-gum or rubber packing-ring, *d'*, so as to make an air-tight joint, and thus prevent the water in the cooler C D from being contaminated by any contact with the air of the provision-chamber *b''*.

By means of the stop-cock *c''* water can at any time be drawn from the containing-cooler C D, a small hole, 3, admitting air for the purpose of allowing the water to flow.

Claim.

I claim as my invention—

The design for a portable water-cooler and refrigerative-vessel combined, substantially as shown and described.

JOHN LIMING.
